(Cl. D15—8)

To all whom it may concern:

Be it known that I, Jack D. Sverdlik, a citizen of the United States, residing at West Hempstead, Long Island, in the county of Nassau and State of New York, have invented a new, original, and ornamental Design for a Combined High Chair and Baby Walker, of which the following is a specification, reference being had to the accompanying drawing forming a part thereof.

In the drawing:

Fig. 1 is a perspective view of a combined high chair and baby walker, showing my new design;

Fig. 2 is a perspective view of the high chair removed from the base; and

Fig. 3 is a perspective view of the base separate from the high chair of the same.

I claim:

The ornamental design for a combined high chair and baby walker, as shown.

JACK D. SVERDLIK.
